UNITED STATES PATENT OFFICE.

ALLEN B. KENDALL, OF MAYWOOD, ILLINOIS.

BLOCK-SIGNALING SYSTEM.

1,258,622.

Specification of Letters Patent.

Patented Mar. 5, 1918.

Application filed August 7, 1913. Serial No. 783,506.

To all whom it may concern:

Be it known that I, ALLEN B. KENDALL, citizen of the United States, residing at Maywood, in the county of Cook and State 5 of Illinois, have invented a certain new and useful Improvement in Block-Signaling Systems, of which the following is a full, clear, concise, and exact description.

My invention relates to a block-signaling 10 system for railways. Its object is to provide a simplified system for controlling automatic signals on a single track road so that a train leaving a station in one direction will set all the signals between that and the 15 next station at the stop position for a train moving in the opposite direction and will also set signals for a train following in the same direction so that said latter train can follow the first train in the same direction 20 but not closer than one block thereto, that is, not closer than the distance between the signals. In short, my invention contemplates an absolute automatic block-signal system with respect to trains traveling in opposite 25 directions on a single track and a permissive automatic block-signal system with respect to trains traveling in the same direction on a single track.

The various features of my invention may 30 be more readily understood by reference to Figures 1 and 2 of the accompanying drawings. By placing said figures end to end with Fig. 2 at the right of Fig. 1, there is disclosed a continuous diagram of circuits 35 and apparatus embodying the preferred form of my invention, said diagram showing the normal condition of the circuits and apparatus for a series of unoccupied blocks between two railway stations.

40 The railway, whether it be for steam or electric cars, may be laid off in the usual manner in a series of blocks, such blocks representing the distance between signals, and each block in turn may be divided into track-sections. Each of said track-sections is electrically divided by the section insulators *a* as is customary. In the drawings I, II, III, IV, V and VI represent six track-sections 45 between the railway stations X and Y, there being two track-sections to each block.

In the single track system illustrated, the several blocks are guarded at each end by a suitable signal mechanism, as for example, by semaphores 1, 3, 5, 7, controlling the traffic 55 in one direction, and 0, 2, 4, 6, controlling the traffic in the opposite direction. Said

semaphore signals and their controlling mechanisms may be of standard construction and are preferably so arranged that when the circuits for their corresponding 60 controlling mechanisms are energized, the signals are set at safety or caution, as the case may be, but upon the said circuits being opened, the corresponding signals are set at danger. 65

The circuits of a system embodying my invention may be best understood by tracing the circuits which control the signals between the two railway stations X and Y, such circuits being duplicated throughout 70 the system.

Each signal has two controlling circuits, one the 45° control for setting the signal at "caution" and the other the 90° control for setting the signal at "clear" or "proceed 75 at full speed." If both of these controlling circuits for the signal be open, then said signal falls to the "danger" or "stop" position.

Referring to the drawings, the signal 1, 80 for example, has its caution or 45° control circuit extending from battery B through the contact *b'* of relay A' to the control apparatus of signal 1, indicated diagrammatically in the drawings and from thence to 85 the wire leading to the opposite pole of the battery. Said signal has its clear or 90° control circuit extending from battery B through contact *e'* of relay C' to said control apparatus and from thence to the wire leading 90 to the opposite pole of the battery. In like manner the controlling circuits for the other semaphore signals may be traced. It will thus be noted that for each signaling mechanism there are two relays, one directly controlling its caution and the other its clear 95 indication. For example, the relay A' opens or closes the contact *b'* in the circuit controlling the caution or 45° control and the relay C' opens or closes contact *e'* in the 100 clear or 90° control of the signal 1.

As above stated the caution or 45° control of signal 1 is under the control of the relay A'. The circuit of said relay A' extends from the wire *w* common to a like pole of the 105 several batteries B, B', B², B³, through said relay A', contact *d'* of relay D', wire *a'* extending to the next block, contact *f'* of relay D², contact *g'* of relay A² to battery B'. There are thus in the circuit of said 110 relay A' three points of control represented by the switch contacts *d'*, *f'* and *g'* respec-

tively. In like manner the circuits of the corresponding relays controlling the circuits of the caution or 45° control of the other signals may be traced.

- 5 As above stated, the clear or 90° control of signal 1 has its control circuit including the relay contact e' of relay C'. The circuit of said relay C' includes the contact h' of relay A' and the wire C' to the next block, 70
 10 the continuity of said wire being under the control of the circuit-breaker E³, which latter is operated by the semaphore signal 3 in the usual manner, that is, closed when signal 3 is at 45° or 90°. The circuit of said relay 75
 15 C' may be traced from the common wire w through said relay C', contact h' of relay A', wire c' , circuit-breaker E³ to battery B'. In like manner the circuit of relay C² includes contact h^2 of relay A² and circuit-breaker E controlled by semaphore o; the 80
 20 relay C³ includes contact h^3 of relay A³ and circuit-breaker E³; and so on with respect to relays C⁴, C⁵, C⁶ and C⁶.

When none of the track-sections between 25 the two sections are occupied, the relays D', D², D³, D⁴, D⁵, D⁶, bridged across the track rails, are energized by current from the corresponding batteries x' , x^2 , x^3 , etc. The relays D', D², D³, etc., are thus energized 30 and close their respective contacts, and the circuit conditions are those represented in the drawings, in which all the signals are shown as set at clear or safety.

The operation of my invention is as follows: A train entering track section I from 35 station X will short circuit the relay D'. The consequent deenergization of said relay will open the contact d' in the circuit of the relay A'. The resulting deenergization of 40 the relay A' opens its contacts b' and h' , the former directly controlling the caution or 45° control of signal 1 and the latter opening the circuit of the relay C', which latter relay, as above described, controls the clear 45 or 90° control of signal 1. Thereupon the signal 1 moves to the danger or stop position.

The above mentioned short circuiting of 50 relay D' by a train entering the track section I also results in the opening of contact f' in the circuit of the relay A². Said latter circuit may be traced from one pole of the battery B through contact f' , wire a^2 contact d^2 , to the common wire w leading to the 55 opposite pole of the battery. The circuit of relay A², being thus opened at contact f' , its contacts b^2 and h^2 are opened. The contact b^2 is in the circuit of the caution or 45° control of signal II; and contact h^2 is in the 60 circuit of the relay C² which controls the contact e^2 , in the circuit of the clear or 90° control of the signal II. Both of said circuits thus being opened, the signal II is moved to the stop position. The deenergization 65 of the relay A² also results in the opening

70 of its contact g^2 which falls upon the insulated surface i of the contact selector F, thereby opening the circuit of the relay A⁴. The circuit of said relay A⁴ may be traced as follows:—from battery B', through contact g^2 of relay A² contact f^3 of relay B³, wire a^4 leading to the next contact d^4 of relay D⁴, winding of relay A⁴, to the common wire w . The deenergization of the relay A⁴ due to its circuit having been opened at g^2 75 of the relay A² results in the opening of contacts g^4 , b^4 , and h^4 , thereby resulting in the setting of the signal IV at the danger or stop position in the same manner as already described with respect to signal II. 80 In like manner the opening of contact g^4 of relay A⁴ opens the circuit of relay A⁶, which, through its contact b^6 and h^6 controls the caution or 45° and the safe or 90° control of signal VI. Said signal VI is 85 thereupon moved to the stop or danger position. Signals II, IV and VI are thus indicating danger or stop to a train moving in an opposite direction from station Y, and thus positive protection is given against a 90 train leaving station Y for station X.

While the train is in track section I, as above described, the signal 1 also is set at stop or danger to a train leaving station X and traveling in the same direction as a 95 train already in section I.

When a train moves from section I into section II, the signals remain set, as above described, since although the circuit for the relay A' becomes closed at contact d' , the 100 circuit for said relay A' is open at contact f^2 of relay D², said latter relay being now shunted by the train in section II. Also, although the circuit of relay A² is closed at contact f' , the circuit of said relay A² is 105 open at contact d^2 of relay D². Therefore, although the train has moved from track section I to track section II, the signals remain as set by the train when it moved into track section I. 110

Assuming next that the train passes from track section II into track section III, the relay D³ is shunted and its armature m^3 falling against the insulated surface i of the metallic contact selector F, mounted 115 upon the end of the flexible steel bar n , will move said selector to the right to such position that when the circuit for the relay A³ is open, the contact spring g^3 thereof will fall against the contact surface of the selector F and will complete the circuit for the relay A'. This completion of the circuit for the relay A' will close the 45° control of signal 1 at contact b' of said relay, thus giving the permissive or caution indication 120 at signal 1, allowing a train to follow one block behind the preceding train.

As above stated, the 90° or clear control for each signal is under the control of a corresponding relay. For example, the 90° con- 130

trol of signal 1 is under the control of the relay C', the circuit of which is controlled at the contact h' of the relay A' and also by the circuit breaker E³ under the control 5 of the semaphore signal 3. Therefore, for the 90° control circuit of signal 1 to be closed, it is not only necessary that the contact h' of relay A' be closed, but it is also necessary that the signal 3 be set either at 10 caution or clear indication. It is obvious that said signal 3 will not move to the caution or 45° position until the train has moved into the block represented by track-section V, whereupon the signal 1 will be moved from 15 caution to clear, thus indicating to a train following that it may proceed at full speed.

It will be noted that the several contact 20 selectors F are of like structure, each being a block of metal secured upon the end 25 of a flexible strip steel n and having upon its slanting sides insulating material i. Thus, when one of the relays bridged across the line becomes deenergized, as for example relay D³, its armature, as for example m³, will fall against the inclined insulated side i 30 of said block F and push it to one side so that when the companion relay, as for example the relay A³ is subsequently deenergized, its armature, as for example the armature d³, will complete the circuit (which would otherwise be broken by the retraction of said armature) through said selector F and the metallic strip n.

It will be noted that the corresponding 35 relays and the contacts controlled thereby are for convenience given corresponding reference letters having exponents corresponding to the number of the track-section. In short, parts similar to those already herein- 40 before described are given similar reference characters having exponents corresponding to the track-sections at which they are located.

It is obvious that my invention is not 45 limited to the specific structure of circuits and apparatus illustrated in the drawings and that changes therein may be made without departing from my invention as defined in the accompanying claims.

50 What I claim is:—

1. In a block-signal system, the combination with a railway having electrically divided track-sections and a source of electric current in bridge of the rails of each track-section: of a track-relay in bridge of each track-section; electrically actuated block-signals; and a signal-control relay for each of said block-signals for controlling the circuits thereof, certain of said signal-control 55 relays having a circuit including a switch under the joint control of a track-relay and a signal-control relay of another block, said switch having a plurality of positions wherein the current may flow in said circuit in the 60 same direction.

2. In a block-signal system, the combination with a railway having electrically divided track-sections and a source of electric current in bridge of the rails of each track-section; of a track-relay in bridge of each 70 track-section; electrically actuated block-signals; and a signal-control relay for each of said block-signals for controlling the circuits thereof, each of said signal-control relays having a circuit including a switch 75 under the control of the corresponding track-relay, and the circuits of certain of said signal-control relays also including a switch under the joint control of a track-relay and a signal-control relay of another 80 block, said switch having a plurality of positions wherein the current may flow in said circuit in the same direction.

3. In a block-signal system, the combination with a railway having electrically divided track-sections and a source of electric current in bridge of the rails of each track-section; of a track-relay in bridge of each track-section; electrically actuated block-signals; a signal-control relay for each of 90 said block-signals for controlling the circuits thereof, certain of said signal-control relays having a circuit including a switch closed by the energization of another of said signal-control relays, said switch, upon the 95 deenergization of said last mentioned signal-control relay, being either closed upon an alternative path or opened dependent upon the energized or deenergized condition of a track-relay at the time of such deenergization of said signal-control relay.

4. In a block-signal system, the combination with a railway having electrically divided track-sections and a source of electric current in bridge of the rails of each track-section; of a track-relay in bridge of each track-section; electrically actuated block-signals; and a signal-control relay for each of said block-signals for controlling the circuits thereof, certain of said signal-control 105 relays having a circuit including a switch having alternative positions independent of the position of a corresponding signal determined by another of said signal-control relays, said circuit being closed through one 110 path in one position of said switch and closed through an alternative path when said switch is moved to its alternative position at a time when a coöperating track-relay is deenergized.

5. In a block-signal system, the combination with a railway having electrically divided track-sections and a source of electric current in bridge of the rails of each track-section; of a track-relay in bridge of each 120 track-section; electrically actuated block-signals; a signal-control relay for each of said block-signals for controlling the circuits thereof, certain of said signal-control relays having a circuit including a switch 125

having alternative positions determined by another of said signal-control relays, said circuit being closed through one path in one position of said switch, a movable contact-selector under the control of a track-relay coöperating with said last mentioned signal-control relay for controlling the closure of said switch through an alternative path in the alternative position of said switch.

6. In a block-signal system for railways, the combination with electrically actuated block-signals, of a track-relay controlled by a car, a movable contact-selector, means controlled by said track-relay for positioning said contact-selector, and a signal-control relay for a distant signal, said signal-control relay having a circuit including a switch comprising a member adapted to contact with a part of said circuit to close said circuit through one path and to coöperate with said movable contact-selector to close said circuit through another path.

7. In a block-signal system, the combination with a railway having electrically divided track-sections and a source of electric current in bridge of the rails of each of said track-sections; of a track-relay in bridge of each track-section; an electrically actuated block-signal corresponding to each of said track-relays, the block-signals of two adjacent track-sections controlling traffic in opposite directions; movable contact-selectors corresponding to certain of said track-relays; means controlled by said last mentioned track-relays for positioning the corresponding movable contact-selectors; and signal-control relays for controlling a circuit of each of said signals, certain of said signal-control relays having a circuit including a switch coöperating with one of said movable contact-selectors.

8. In a block-signal system, the combination with a railway having electrically divided track-sections and a source of electric current in bridge of the rails of each of said track-sections; of a track-relay in bridge of each track-section; an electrically actuated block-signal corresponding to each of said track-relays, the block-signals of two adjacent track-sections controlling traffic in opposite directions; a 45° control-relay for controlling a circuit of each of said signals, certain of said 45° control-relays having a circuit including a switch under the control of the corresponding track-relay and a switch member under the control of another of said 45° control-relays and means coöperating with the said last-named member to maintain said circuit when said last-named relay is deënergized.

9. In a block-signal system, the combination with a railway having electrically divided track-sections and a source of electric current in bridge of the rails of each of said

track-sections; of a track-relay in bridge of each track-section; an electrically actuated block-signal corresponding to each of said track-relays, the block-signals of two adjacent track-sections controlling traffic in opposite directions; a 45° control-relay for controlling a circuit of each of said signals, certain of said 45° control-relays having a circuit including a switch under the control of the corresponding track-relay, a switch member under the control of another of said track-relays, and a switch, under the control of another of said 45° control-relays and means coöperating with the said last-named member to maintain said circuit when said last-named relay is deënergized.

10. In a block-signal system, the combination with a railway having electrically divided track-sections and a source of electric current in bridge of the rails of each of said track-sections; of a track-relay in bridge of each track-section; an electrically actuated block-signal corresponding to each of said track-relays, the block-signals of two adjacent track-sections controlling traffic in opposite directions; a 45° control-relay for controlling a circuit of each of said signals, certain of said 45° control-relays having a circuit including a switch under the control of the corresponding track-relay and a switch under the control of a track-relay of an adjacent track-section, and a switch member under the control of a 45° control-relay of an adjacent block and means coöperating with the said last-named member to maintain said circuit when said last-named relay is deënergized.

11. In a block-signal system, the combination with a railway having electrically divided track-sections and a source of electric current in bridge of the rails of each track-section; of a track-relay in bridge of each track-section; electrically actuated block-signals; a signal-control relay for each of said block-signals for controlling the circuits thereof, certain of said signal-control relays having a circuit including a switch closed by the energization of another of said signal-control relays, means dependent upon the deënergization of a track relay prior to the deënergization of said last mentioned signal control relay for causing said switch to preserve said circuit, upon the deënergization of said last mentioned signal control relay.

12. In a block-signal system, the combination with a railway having electrically divided track-sections and a source of electric current in bridge of the rails of each track-section; of a track-relay in bridge of each track-section; electrically actuated block-signals; a signal-control relay for each of said block-signals for controlling the circuits thereof, certain of said signal-control relays having a circuit including a switch

closed by the energization of another of said signal-control relays, means controlled by a track relay for causing said switch to preserve said circuit upon the deenergization 5 of said last mentioned signal-control relay.

13. In a block-signal system, the combination with a railway having electrically divided track-sections and a source of electric current in bridge of the rails of each track-section; of a track-relay in bridge of each track-section; electrically actuated block-signals; and a signal-control relay for each of said block-signals for controlling the circuits thereof, certain of said signal-control 10 relays having a circuit including a switch having alternative positions determined by another of said signal-control relays, said circuit being closed through one path in one position of said switch and closed through an alternative path to permit the current to 15 flow in said circuit in the same direction when said switch is moved to its alternative position at a time when a coöperating track-relay is deenergized.

14. In a block-signal system, the combination with a railway having electrically divided track-sections and a source of electric current in bridge of the rails of each track-section; of a track-relay in bridge of each track-section; electrically actuated block-signals; and a signal-control relay for each of said block-signals for controlling the circuits thereof, certain of said signal-control 20 relays having a circuit including a switch having alternative positions determined by another of said signal-control relays, said circuit being closed through one path in one position of said switch and closed through an alternative path when said switch is 25 moved to its alternative position only at a time when the corresponding track-relay is deenergized.

15. In a block-signal system, the combination with a railway having electrically divided track-sections and a source of electric current in bridge of the rails of each track-section; of a track-relay in bridge of each track-section; electrically actuated block-signals; a signal-control relay for each of 30 said block-signals for controlling the circuits thereof, certain of said signal-control relays having a circuit including a switch having alternative positions determined by another of said signal-control relays, said circuit being closed through one path in one position of said switch, and means controlled 35 by the track relay for closing said circuit through said switch when said switch is in its alternative position.

16. In a block signal system for railways, the combination with electrically actuated block-signals, of a track-relay controlled by a car, a movable contact-selector, means controlled by said track-relay for positioning 40 said contact-selector, and a signal-control

relay for a distant signal, said signal-control relay having a circuit including a switch coöperating with said movable contact-selector, and a signal-control relay for another signal controlling said switch. 70

17. In a block-signal system, the combination with a railway having electrically divided track-sections and a source of electric current in bridge of the rails of each track-section; of a track-relay in bridge of each track-section; electrically actuated block-signals; and a signal-control relay for each of said block-signals for controlling the circuits thereof, certain of said signal-control relays having a circuit including a switch, 75 comprising two members, one of which is under the control of the track-relay and one of which is under the control of the signal-control relay.

18. In a railway signaling, a stretch of 80 single track, signals located at intervals for governing traffic in one direction through the stretch and other signals located at intervals for governing traffic in the other direction through the stretch, a signal relay 85 for the control of each signal, a circuit for each signal relay, switches in certain of said circuits and controlled by the signal relay for the signal respectively next in advance governing traffic in the same direction, track- 90 relays connected with the stretch for the control of the signal relay circuits, and means for rendering certain of said switches effective to prevent the signal-relay in the rear of a car or train from controlling the 95 signal relays for the signals in the rear which govern traffic in the same direction. 100

19. In railway signaling, a stretch of single track, signals located at intervals for governing traffic in one direction through 105 the stretch and other signals located at intervals for governing traffic in the other direction through the stretch, a signal relay for the control of each signal, a circuit for each signal-relay, switches in certain of said 110 circuits and controlled by the signal relay for the signal respectively next in advance governing traffic in the same direction, track-relays connected with the stretch for the control of the signal relay circuits, and means 115 controlled by a track relay for rendering certain of said switches effective to prevent the signal-relay in the rear of a car or train from controlling the signal relays for the signals in the rear which govern traffic in the same 120 direction.

20. In combination, a stretch of railway track, signals located at intervals for governing traffic through said stretch, a signal relay for each signal, switches for controlling certain of said signal relays and controlled by the signal relays for the signals respectively next in advance, track circuits for the stretch including relays for controlling the signal relays and means for render- 125 130

- ing certain of said switches effective to prevent said signal relays from controlling the signal relays respectively for the signals next in the rear.
- 5 21. In railway signaling, a stretch of single track, signals located at intervals for governing traffic in one direction through the stretch and other signals located at intervals for governing traffic in the other directions through the stretch, circuits for the signals, and switches controlled by a car or a train in the stretch for opening the circuits of the signals in advance of the car or train governing traffic in a direction opposite to 10 the direction of movement of the car or train and the circuit of a signal in the rear of the car or train governing traffic in the direction of movement of the train and means for rendering certain of said switches effective 15 to preserve the circuits of other signals in the rear of the car or train governing traffic in the direction of movement of the car or train.
22. In railway signaling, a stretch of single track, signals located at intervals for governing traffic in one direction through the stretch and other signals located at intervals for governing traffic in the other direction through the stretch, a signal relay 25 for the control of each signal, a circuit for each signal relay each of which circuits includes a switch controlled by the signal relay for the next signal in advance governing traffic in the same direction, track relays connected with the stretch for controlling the circuits of the signal relays, a branch for each of certain of the signal relay circuits, and means for causing said switches to close said circuits through said 30 branches when said circuits are opened by the action of said signal relays.
23. In railway signaling, a stretch of single track, signals located at intervals for governing traffic in one direction through the stretch and other signals located at intervals for governing traffic in the other direction through the stretch, a signal relay for the control of each signal, a circuit for each signal relay each of which circuits includes a switch controlled by the signal relay for the next signal in advance governing traffic in the same direction, track relays connected with the stretch for controlling the circuits of the signal relays, a branch for 35 each of certain of said signal relay circuits, and means controlled by said track relays for causing said switches to close said circuits through said branches when said circuits are opened by the action of said signal relays.
24. In combination, a stretch of railway track over which traffic moves in both directions, signals located at intervals for governing traffic in one direction through said 40 stretch, a signal relay for the control of each
- signal, a circuit for each relay each of which circuits includes a switch controlled by the relay for the signal next in advance, track circuits for the stretch including track relays for controlling said signal relay circuits, a branch for each of certain of said signal relay circuits, and means for causing said switches to close said circuits through said branches when said circuits are opened by the action of said signal relays. 75
25. In combination, a stretch of railway track, signals located at intervals for governing traffic through said stretch, a signal relay for each signal, a circuit for each relay, switches in certain of said circuits and controlled respectively by signal relays, and means for causing certain of said switches to preserve said circuits upon cessation of the action of said last named relays to hold said signal-relay circuits closed. 80
26. In combination, a stretch of railway track, signals located at intervals for governing traffic through said stretch, a signal relay for each signal, a circuit for each relay, switches in certain of said circuits and controlled respectively by signal relays, track circuits for the stretch including track-relays, contact members connected to said signal relay circuits and moved by said track relays to coöperate with said switches to preserve said circuits upon cessation of the action of one of said signal relays tending to hold another of said signal relay circuits closed. 85
27. In combination, a stretch of railway track, signals located at intervals for governing traffic through said stretch, a signal relay for each signal, a circuit for each relay, movable switch members connected to one part of certain of said circuits and making contact with another part thereof to complete said circuit, contact selectors connected to said last named part of certain of said circuits and means controlled by said track-relays for positioning said selectors to contact with said switch members when said members move to break their respective circuits. 90
28. In combination, a stretch of railway track, signals located at intervals for governing traffic through said stretch, a signal relay for each signal, a circuit for each relay, movable switch members connected to one part of certain of said circuits and making contact with another part thereof to complete said circuit, armatures for said track relays and contact selectors comprising a body member having a face inclined to the direction of movement of and adapted to be acted upon by one of said armatures, a flexible support for said body member and a contact carried thereby and connected to one of the said last named parts of certain of said circuits and adapted to be brought into the path of one of said members by the ac- 95

- tion of one of said armatures upon said inclined face.
29. In a signaling system, a signal circuit, a movable switch member forming a portion thereof, said member being connected to one part of said circuit and adapted to contact with another part of said circuit to close said circuit through one path, a second circuit including a relay, an armature controlled thereby, a movable contact connected to said last named part of said first named circuit and adapted to be moved into the path of said member by said armature to close said first-named circuit through another path.
30. In a signaling system, a circuit, a switch member normally closing said circuit through one path and movable to break said circuit, a contact-selector connected to a part of said circuit and adapted to be moved into the path described by said switch during its movement to open said circuit, whereby the opening movement of said switch brings it into contact with said contact-selector to close said circuit through another path.
31. In a signaling system, a circuit, a switch member normally closing said circuit through one path and movable to break said circuit, a contact-selector connected to a part of said circuit and normally positioned out of the path described by said switch during its opening movement, a second circuit including a relay, means controlled by said relay for moving said contact-selector into the path of said switch, whereby said first-named circuit is closed through another path by the opening movement of said switch.
32. In a signaling system, a circuit, a switch member normally closing said circuit through one path and movable to break said circuit, a contact-selector connected to a part of said circuit and adapted to be moved into the path described by said switch during its movement to open said circuit, whereby the opening movement of said switch brings it into contact with said contact-selector to close said circuit through another path, said switch and contact-selector being so relatively positioned that the opening made in the first path by movement of the switch is of the same magnitude whether or not said contact-selector is positioned to coöperate with said switch to close said circuit through said second path.
33. In a block signal system, the combination with a railway having electrically divided track sections, a source of electric current in bridge of the rails of each track-section and a track relay in bridge of each track-section, of electrically-actuated block signals, signal control circuits for certain of said signals, switches for controlling said signal control circuits, a selecting device set in operative condition by the action of a track relay, and means coöoperating with

said selecting device and set into action upon the opening of one of said switches to close the gap formed in one of said signal-control circuits by the opening of one of said switches.

70

34. In a block signal system, the combination of a railway having electrically divided track sections, a source of electric current in bridge of the rails of each track section and a track relay in bridge of each track section, of electrically-actuated block signals, signal-control circuits for certain of said signals, switches for controlling said signal-control circuits, a normally open auxiliary circuit, a selecting device set into operative condition by the action of a track relay, and means controlled by a signal-control circuit for coöperating with said selecting device to close said auxiliary circuit around the gap formed in one of said signal-control circuits by the opening of one of said switches.

35. In a block signal system, the combination of a railway having electrically divided track sections, a source of electric current in bridge of the rails of each track section and a track relay in bridge of each track section, of electrically-actuated block signals, signal-control circuits for certain of said signals, switches for controlling said signal-control circuits, a selecting device set in operative condition by the action of a track relay, and means dependent upon the condition of said selecting device and of one of said signal-control circuits for neutralizing the effect of the opening of one of said switches in said signal-control circuits.

90

36. In a block signal system, the combination with a railway having electrically divided track-sections, a source of electric current in bridge of the rails of each section and a track relay in bridge of each track-section, of electrically-actuated block signals, a signal control relay for each signal, circuits for said signal control relays, switches in certain of said circuits and controlled by the signal relay for the signal respectively next in advance governing traffic in the same direction, whereby a gap may be made in the circuit of a signal control relay, a normally open auxiliary circuit around said gap, a member movable to a plurality of positions under the action of one of said track relays, and means dependent upon the position of said member and set in motion by the deënergization of a signal control relay to close said auxiliary circuit around the gap made by the opening of the switch controlled by said last-named signal control relay.

track-section, of electrically-actuated block signals, a signal control relay for each signal, circuits for said signal control relays, switches in certain of said circuits and controlled by the signal relay for the signal respectively next in advance governing traffic in the same direction, whereby a gap may be made in the circuit of a signal control relay, a normally open auxiliary circuit around said gap, and means to close said auxiliary circuit around the gap made by the opening of one of said switches, said means including a part set into motion by the deenergization of a signal control relay 10 and a member under control of a track relay, said member having a plurality of positions, in one of which it co-operates with said part, the operativeness of said means to close said auxiliary circuit being dependent upon said member occupying a position wherein it co-operates with said part at the time of deenergization of said last-named signal control mechanism.

38. In a block signal system, the combination with a railway having electrically divided track-sections, a source of electric current in bridge of the rails of each section and a track relay in bridge of each track-section, of electrically-actuated block signals, a signal control relay for each signal, circuits for said signal control relays, switches in certain of said circuits and controlled by the signal relay for the signal respectively next in advance governing traffic in the same direction, whereby a gap may be made in the circuit of a signal control relay, a normally open auxiliary circuit around said gap, and means to close said auxiliary circuit around the gap made by the opening of one of said switches, said means including a part set in motion by the deenergization of a signal control relay and a member movable to positions within and without the path of said part and under the control of a track relay, the operativeness of said means to close said auxiliary circuit being dependent upon the position of said member at the time of deenergization of said last-named signal control relay.

50 39. In a block signal system, the combination with a railway having electrically divided track-sections, a source of electric current in bridge of the rails of each section and a track relay in bridge of each track-section, of electrically-actuated block signals, a signal control relay for each signal, circuits for said signal control relays, switches in certain of said circuits and controlled by the signal relay for the signal respectively next in advance governing traffic

in the same direction, whereby a gap may be made in the circuit of a signal control relay, a normally open auxiliary circuit around said gap, and means to close said auxiliary circuit upon deenergization of a signal control relay, said means including mechanism having operative and inoperative settings and controlled by a track relay, the operativeness of said means to close said auxiliary circuit being dependent upon the setting of said mechanism at the time of deenergization of said last-named signal control relay.

40. In a signaling system, a circuit, a switch member normally closing said circuit through one path and movable to make and break said circuit, a contact-selector connected to a part of said circuit and adapted to be moved into and out of the path described by said switch during its movement, whereby the movement of said switch brings it into contact with said contact-selector to close said circuit through another path dependent upon the position of said selector.

41. In a signaling system, a circuit, a switch member normally closing said circuit through one path and movable to make and break said circuit, a contact-selector connected to a part of said circuit and adapted to be moved into and out of the path described by said switch during its movement to open said circuit, whereby the opening movement of said switch brings it into contact with said contact-selector to close said circuit through another path dependent upon the position of said selector.

42. In a signaling system, a circuit, a movable switch member connected to one portion of said circuit, a contact-selector connected to another portion of said circuit and adapted to be moved into and out of the path described by said switch member during its movement, whereby the movement of said switch member brings it into contact with said contact-selector to close said circuit dependent upon the position of said selector, said switch member and contact-selector being so relatively positioned that the movement of the switch member is unaffected whether or not said contact-selector is positioned to co-operate with said switch member to close said circuit.

In witness whereof I hereunto subscribe my name this 5th day of August, A. D., 1913.

ALLEN B. KENDALL.
